Primary Examiner — Ruth McInroy(74) *Attorney, Agent, or Firm* — Michael Best & Friedrich LLP(57) **CLAIM**

We claim the ornamental design, as shown.

DESCRIPTION

FIG. 1 is a perspective view of a brush for a cleaning device showing our new design;

FIG. 2 is a first side view of the brush of FIG. 1.

FIG. 3 is a second side view of the brush of FIG. 1.

FIG. 4 is a third side view of the brush of FIG. 1.

FIG. 5 is a fourth side view of the brush of FIG. 1.

FIG. 6 is a first end view of the brush of FIG. 1; and,

FIG. 7 is a second end view of the brush of FIG. 1.

The dash-dot-dashed lines represent unclaimed boundary lines. The details shown in broken lines form no part of the claimed design.

1 Claim, 6 Drawing Sheets(56)
